United States Patent Office

Des. 222,050
Patented Sept. 28, 1971

222,050

STEERING WHEEL AID

Joseph Romanoski, 48 Craven St.,
Huntington Station, N.Y. 11746

Filed Apr. 9, 1970, Ser. No. 22,347

Term of patent 7 years

Int. Cl. D12—14

U.S. Cl. D14—30

FIG. 4

FIG. 5

FIG. 1

FIG. 2

FIG. 3

FIG. 1 is a perspective view of the steering wheel aid;
FIG. 2 is a front view of the steering wheel aid;
FIG. 3 is a right-side view of the steering wheel aid;

FIG. 4 is a top view of the steering wheel aid; and
FIG. 5 is a bottom view of the steering wheel aid.

The side and the rear views not shown are substantially the same as the side and front, respectively, which are shown.

I claim:

The ornamental design for a steering wheel aid, substantially as shown and described.
